DESIGN FOR A GAME BOARD

Julius Sears, Dearborn, Mich.

Application April 30, 1941, Serial No. 100,712

Term of patent 7 years

To all whom it may concern:

Be it known that I, Julius Sears, a citizen of the United States, residing at Dearborn, in the county of Wayne and State of Michigan, have invented a new, original, and ornamental Design for a Game Board, of which the following is a specification, reference being had to the accompanying drawing, forming a part thereof, in which:

Fig. 1 is a top plan view of a game board showing my new design;

Fig. 2 is an edge elevational view of the game board disclosed in Fig. 1.

I claim:

The ornamental design for a game board, substantially as shown.

JULIUS SEARS.
